UNITED STATES PATENT OFFICE.

EDMUND J. CORKERY, OF GRAND RAPIDS, MICHIGAN.

CORK-PULLER.

1,093,768.

Specification of Letters Patent. Patented Apr. 21, 1914.

Application filed September 11, 1913. Serial No. 789,391.

To all whom it may concern:

Be it known that I, EDMUND J. CORKERY, a citizen of the United States of America, residing at Grand Rapids, in the county of Kent and State of Michigan, have invented certain new and useful Improvements in Cork-Pullers; and I do hereby declare the following to be a full, clear, and exact description of the invention, such as will enable others skilled in the art to which it appertains to make and use the same.

My invention relates to improvements in cork pullers, and its object is to provide a device of this character which may be cheaply made; which will effectively remove corks from bottles without breaking the cork, and with small manual effort; and to provide the device with various new and useful features hereinafter more fully described and particularly pointed out in the claims, reference being had to the accompanying drawings, in which:—

Figure 1 is a plan view of a device embodying my invention; Fig. 2 is a section of the same on the line 2—2 of Fig. 1; Fig. 3 illustrates the device in position to pull a cork which is wholly within the neck of a bottle; and Fig. 4 shows the puller gripping a cork which projects out of the neck of the bottle.

Like numbers refer to like parts in all of the figures.

This cork puller comprises a pair of pliers having jaws 1 and 2 pivoted together by a bolt 3 and actuated by handles 4. The tips of the jaws 1 and 2 are provided with inwardly projecting prongs 1^a and 2^a adapted to grip a cork 5. A cork screw 6 is attached to a plate 7 which is interposed between the jaws 1 and 2 at their pivotal connection and the pivot bolt 3, which is preferably removable, passes through the said plate. The cork screw 6 extends between the jaws 1 and 2 and is long enough to project beyond the same.

This device may be operated under various conditions, as for example, when the cork to be removed is wholly within the neck 8 of the bottle, the jaws may be opened widely as illustrated in Fig. 3 and the cork screw 6 inserted in the cork until the opened jaws engage the end of the bottle, and will act as levers engaging the end of the bottle and will withdraw the cork until its end projects from the bottle. The jaws may then be closed so that the spurs 1^a and 2^a

thereon will grip the end of the cork and assist in withdrawing the same.

If the operator desires, he may, in removing a cork which is wholly within the bottle as above described, close the jaws before inserting the cork screw in the cork, and by turning the said screw the jaws will engage the mouth of the bottle preventing further downward movement, and further turning of the screw will raise the cork to the mouth of the bottle by the action of the screw in the cork. This will loosen the cork sufficiently so that it can then be withdrawn by pulling on the handles.

It is obvious, of course, that if the cork already projects from the bottle, it is merely necessary to insert the cork screw therein and grip the projecting end with the prongs, on the jaws and draw the cork by pulling on the handles, the prongs assisting the screw to hold to the cork.

It will be seen that this device provides means whereby any cork, no matter how firmly inserted in the bottle, may be easily withdrawn, and furthermore the jaws will grip the cork on its periphery and aid the cork screw and prevent pulling the screw out of the cork.

If the cork screw should accidentally become broken the plate 7 may be removed by removing the pivot bolt 3 and a new plate and cork screw substituted.

What I claim is:—

1. A cork puller, comprising a pair of pliers, one member of which serves as a lever to engage the mouth of a bottle and a cork screw attached to said member and adapted to enter a cork in said bottle.

2. A cork puller, comprising a pair of pliers and a cork screw attached to said pliers and extending between the jaws thereof, said pliers being adapted to engage the mouth of a bottle to act as a lever to raise the cork and to grip the cork to aid the cork screw.

3. A cork puller, comprising a pair of pliers having prongs on its jaws and a cork screw attached to said pliers and extending between the jaws thereof, said pliers being adapted to engage the mouth of a bottle to act as a double lever to raise the cork and to grip the cork to aid the cork screw.

4. A cork puller, comprising a pair of pliers and a cork screw pivotally attached to said pliers at their pivotal connection, and extending between the jaws of the same, said

pliers being adapted to engage the mouth of a bottle to act as a double lever to raise the cork or to engage the cork to aid the cork screw.

5. A cork puller, comprising a pair of pliers having prongs on its jaws, a removable pivot bolt to connect said jaws, and a cork screw pivotally attached to said pliers by said pivot bolt, said jaws being adapted

to engage the mouth of a bottle to act as a double lever to raise the cork or to engage said cork to aid the cork screw.

In testimony whereof I affix my signature in presence of two witnesses.

EDMUND J. CORKERY.
